DESIGN FOR A CURTAIN OR THE LIKE

Max Sadinoff, Brooklyn, N. Y.

Application August 30, 1934, Serial No. 53,116

Term of patent 3½ years

To all whom it may concern:

Be it known that I, MAX SADINOFF, a citizen of the United States, residing at 1766 Union Street, in the Borough of Brooklyn, in the city of New York, county of Kings, and State of New York, have invented a new, original, and ornamental Design for a Curtain or the like, of which the following is a specification, reference being had to the accompanying drawing, forming a part thereof.

Fig. 1 is a plan view of a curtain showing my new design. The stippling represents substantially solid material superimposed upon a mesh

background as represented by the interrupted cross hatching.

Fig. 2 is a detailed view of a portion of a curtain as illustrated in Fig. 1, showing the mesh background upon which the solid material is superimposed.

I claim:

The ornamental design for a curtain or the like as shown and described.

In testimony whereof I have signed this specification.

MAX SADINOFF.
